ABSTRACT OF THE DISCLOSURE

A combination gauge and cementing device for accurately locating an outsole relative to a lasted slipper upper to which it is to be cemented.

Background of the invention

The invention herein relates to the art of making slippers, and more particularly, to means for accurately gauging the location of an outsole relative to a lasted slipper upper to which it is to be cemented.

While it has been proposed to provide gauging means in shoe sole cementing machines, such known devices are of rather complicated structure, costly to fabricate and require relatively skilled operators to utilize the same.

Accordingly, an object of this invention is to provide an improved sole gauge and cementing device which is of simple construction, inexpensive to manufacture, highly flexible in its application to shoes and slippers of varying sizes; and which may be used by operators of relatively nominal skill.

Other objects of this invention will in part be obvious and in part hereinafter pointed out.

Summary of the invention

The device of the instant invention comprises essentially a pad of semi-hard rubber or the like, together with a plurality of sets of toe and heel gauges which are removably associated with the pad for positioning an adhesive coated shoe or slipper outsole on the pad. The gauges are further adapted to accurately locate the shoe or slipper upper relative to the positioned outsole, pressure being then applied to the lasted upper to effect a cementing action between the outsole and the upper.

Brief description of the drawing

FIG. 1 is a top plan view of a sole gauge and cementing device embodying the invention;

FIG. 2 is a transverse sectional view taken on the line 2—2 of FIG. 1; and

FIG. 3 is a longitudinal sectional view taken on the line 3—3 of FIG. 1.

Description of the preferred embodiment

As shown in the drawing, 10 designates a sole gauge and cementing device embodying the invention. The same comprises a rectangular pad 11 of rubber or other elastomeric material having a desired degree of resiliency, which may be of the order associated with semi-hard rubber. The pad 11 is located within an open top holder 12.

A pair of laterally related, upstanding locating studs 13 are fixed in the upper surface 14 of pad 11, the same being located adjacent the forward corners 15 of said pad. A second pair of laterally related, upstanding locating studs 16 are also fixed in the surface 14 of pad 11, and are located adjacent the rear corners 17 thereof.

A series of toe and heel gauges are provided for mounting on pad 11; each pair of toe and heel gauges being correlated for either a left or right hand slipper or shoe,

2

as well as a predetermined size thereof. Thus, the toe gauge generally indicated at 20, is formed of molded synthetic resin or the like, and has a transverse forward edge 21, side edges 22 and a toe shaped notch 23. The gauge 20 is formed with a pair of laterally spaced through openings 24 which are adapted to register with locating studs 13 on pad 11, to position the same thereon.

A heel gauge, generally indicated at 25, is also formed of molded synthetic resin or the like; and has a transverse rear edge 26, side edges 27 and a heel shaped cutout 28 extending inwardly from the forward transverse edge thereof. Gauge 25 is formed with a pair of laterally spaced through openings 29 which are adapted to register with studs 16 on pad 11, to locate the gauge on said pad. A pair of laterally related upper abutment blocks 30 are secured to the top surface of the heel gauge 25, being located immediately adjacent rear edge portions of the heel cutout 28 therein.

A thin plastic template 31 formed with a toe shaped notch 32 is provided for application to the top surface 14 of pad 11 at an appropriate location thereon; or alternatively, to the underside of toe gauge 20.

It is understood that device 10 is adapted to be used with an associated pressure applying means, such as a vertically positioned ram member 35 having depending therefrom a rear pressure applying member 36 and a front pressure applying member 37; said members 36, 37 having threaded engagement with ram member 35 by way of stem portions 38, 39, thus providing for adjustment of the operative positions of members 36, 37.

The device 10 is used with a last L carrying an upper U thereon; the lower marginal portions 40 thereof being inturned on the sole portion 41 of the last, in the usual manner. In use of the device 10, cement is applied to the outer surface of upper portions 40 and the outsole 42 which is to be attached to upper U, is precoated with adhesive in the usual manner.

The outsole 42 is then located on pad 11 between the gauges 20, 25, and in particular, the toe portion thereof is received in the notch 32 of template 31. The ram member 35 is moved downwardly by suitable means, not shown, to cause pressure applying members 36, 37 to respectively abut the rear top portion of last L and a forwardly disposed lasted upper portion. Continued downward movement of ram member 35 provides pressure to adhere outsole 42 to the inturned marginal portions 40 of the lasted upper U.

It will be apparent that device 10 provides for rapid interchange of toe and heel gauges to suit the particular lasted upper in respect to left or right hand, as well as size. The abutment blocks 30 as well as template 31 facilitates the location of both outsole and lasted upper on the device.

I claim:

1. A sole cementing and gauging device comprising a pad, a toe gauge member, a heel gauge member, cooperating means on said pad and said members for removably mounting said gauge members on the top surface of said pad in longitudinally spaced relation to each other, said cooperating mounting means comprising first and second pairs of laterally related stud members upstanding from the top surface of said pad, said pairs of stud members being in longitudinally displaced relation to each other, and each of said gauge members being formed with a pair of laterally related through openings for receiving therein a pair of said stud members, and toe template means disposed between said toe gauge member and the top surface of said pad for locating the toe portion of a cement coated outsole disposed on said pad between said gauge members, said gauge members being adapted to receive therebetween a last carrying an upper thereon with

marginal edge portions of said upper turned inwardly along bottom marginal portions of the last, whereby the inturned marginal edge portions of the upper are located over and in contact with marginal edge portions of said outsole for adherence thereto.

2. A device as in claim 1 wherein said toe gauge member is formed with a toe shaped notch opening on a rear edge thereof, said heel gauge member being formed with a heel shaped cutout opening on a forward edge thereof, and a pair of laterally related abutment members mounted

on said heel gauge member and located at peripheral edge portions of the cutout therein.
